TREATMENT OF ENRICHED BENZOL WASH
OIL OR THE LIKEAdolf Schmalenbach, Essen, Germany, assignor,
by mesne assignments, to Koppers Company,
Pittsburgh, Pa., a corporation of DelawareApplication October 7, 1938, Serial No. 233,721
In Germany October 7, 1937

1 Claim. (Cl. 196—75)

The present invention relates to the continuous treatment of liquids containing certain substances, for instance, wash oil enriched with benzol or other hydrocarbons, by means of distillation in the presence of steam for the recovery of valuable products from said liquids or wash oil.

For the recovery of benzol and other valuable hydrocarbons from coal distillation gases or the like it is customary to wash the gas to be treated with a suitable solvent such as tar oil. The solvent or tar oil absorbs the benzol hydrocarbons which, after the oil is sufficiently enriched with hydrocarbons absorbed from the gas treated, are separated from the solvent by a distillation in the presence of steam. The oil regenerated in this way may be used again for the gas washing. The vapours of hydrocarbons driven off from the enriched wash oil are condensed and/or purified by rectification or by any other suitable treatment.

For the treatment of the enriched wash oil, distillation in the presence of steam is generally used by means of which the boiling temperatures are reduced to such a degree that a dangerous decomposition of the valuable oil constituents is prevented. It is common practice to add, during the distillation in the presence of steam, so much steam that the wash oil and the wash oil vapours, respectively, are not subject to a temperature higher than to about 140 degrees centigrade. In order to maintain such low distillation temperatures it is necessary to distil in the presence of large amounts of steam but this, on the other hand, makes the fractionating of the vapours, i. e. the separation of the distillate into several fractions of sharply defined boiling limits, practically impossible.

The main object of my invention is to develop improvements by means of which the problem of carrying out the continuous treatment of enriched benzol wash oil or the like, for the purpose of recovering hydrocarbons absorbed by the wash oil in several well defined fractions, is solved in such a manner that, although the distillation in the presence of steam is made use of and advantageously with regard to preventing the decomposition of the washing agent, the absorbed hydrocarbons are nevertheless obtained in various fractions of sharply defined boiling limits.

My present invention provides for this purpose substantially the process as set forth and explained in the following:

First of all the absorbed hydrocarbons of the enriched wash oil or the other solvent are driven

off in continuous operation by distillation in the presence of steam, and the vapours thus distilling over are then condensed wholly or partly, whereupon the condensate (primary product), after the water is separated therefrom, is heated and vaporized in a continuous heater (pipe still), preferably to a temperature of about 230 to 240° C., and the vapours thus formed are introduced into a rectifier column with a small quantity of steam and treated in such a manner that at the top of the rectifier column, the vapours consisting of the lowest boiling constituents for instance crude benzol, escape, such vapours containing about 8% of steam or less (based upon benzol vapours).

15 A distinct difference between the method of working according to the present invention and the heretofore known process, consists in that the so-called primary products, that is, the mixture of wash oil and of hydrocarbons absorbed from the gas escaping from the distilling apparatus, are heated at a comparatively high temperature (about 230—240° C. before the mixture is delivered to the rectifier column. This distilling temperature is considerably higher than the temperature 20 limit which heretofore was considered as being permissible. Surprisingly it was found, however, that the so-called primary product is able to withstand such a high heat treatment without causing any dangerous effects upon the wash-oil contained therein. The wash oil constituents in the primary product show a considerably lower tendency to decompose and this is probably due to the nature of the light hydrocarbons absorbed from the gas and present in large quantities in the primary product.

Another important feature according to the present invention consists in limiting the addition of steam to the rectifier column. It was found that with an addition of steam calculated 40 according to the present invention it is possible to obtain at the top of the rectifier column an extraordinarily pure crude benzol or other low boiling fractions, and at other points of the column correspondingly sharp fractions of another kind, such as toluol, solvent naphtha, and a residual oil highly enriched with naphthalene, from which the naphthalene crystallizes out without any difficulty upon the cooling of the residue to normal temperature.

50 If based, for instance, upon benzol enriched wash oil containing 0.25% of water and 2.4% of constituents distilling over up to 180° C., and producing therefrom the so-called primary product which begins to boil at 85° C. and which contains 45% of constituents distilling over up to 180° C.

by the method in which distillation is in the presence of steam, the vapours are cooled down, and the water is decanted, there can be recovered in the rectifier column the following fractions according to the process of my present invention:

Crude benzol:

Initial boiling temperature 76° C.
Final boiling temperature 108° C.
95-96% boiling up to 100° C.

Toluol:

Initial boiling temperature 100° C.
Final boiling temperature 128° C.
95-96% boiling up to 120° C.

Solvent naphtha:

Initial boiling temperature 135° C.
Final boiling temperature 195° C.
95% boiling up to 180° C.

Residual fraction rich in naphthalene:

Initial boiling temperature 175° C.
0.15% boiling up to 180° C.

The wash oil condensate (primary product) is thereby driven off during vaporization in such a manner that the oil after such a treatment contains only 0.25% water and 0.15% constituents boiling up to 180° C.

Still further objects and features of my present invention may be taken from the following description of a preferred embodiment thereof and from the accompanying drawing which illustrates schematically an apparatus arrangement for carrying out the process according to the present invention.

The enriched wash oil coming from the gas scrubber, not shown on the drawing, first of all flows through the pipe line 1 into a heater 2 provided with coils, through which the oil to be heated flows. Here the wash oil is very quickly heated, preferably to a temperature of about 160 to 180° C. It may be noted that the oil will be heated without any harmful decomposition to a temperature somewhat higher than in the ordinary heating apparatus in which the oil is only slowly moved. A much higher temperature will therefore improve the action of driving off of the hydrocarbons absorbed by the oil from the gas treated. The preheated wash oil treated in the furnace 2, which is similar to a known pipe still, then passes through the pipe line 3 into the distilling column 4 into which stream is added from below through the pipe line 5. The denuded wash oil, freed from the absorbed hydrocarbons, flows from the lowest section of the column 4 through the pipe line 6 into the collecting main 7 for denuded wash oil, and may be led back again to the gas scrubber, after suitable cooling down, or other treatment if desired.

The vapours developed in the column 4 flow through the pipe line 8 into the primary product cooler 9 where they are condensed. The condensate, i. e., the so-called primary product, reaches a water separator 10 from where the condensate, freed from water, and consisting of a certain quantity of wash-oil and of the hydrocarbons absorbed by the oil both of which were driven off in the column 4, may be discharged through the pipe line 11.

The pipe line 11 leads to a heater 12 which is constructed similarly to a pipe still. The condensate is heated up in this pipe still so that it vaporizes. The temperature of the oil in the pipe still may be raised for instance to about 230-240° C. The hot primary product and the vapours formed pass through the pipe line 13 into a rectifier column 14 into which a certain quan-

tity of steam is introduced from below through the pipe line 15.

The temperature of the oil at the inlet of the rectifier column 14, and the quantity of steam added through the pipe line 15, are so calculated that the lower boiling hydrocarbons are evaporated, and that at the top of the column 14, through the pipe line 16, a vapour mixture is withdrawn which has a temperature of about 69-72° C. This vapour mixture consists of a benzol fraction boiling between 76 and 108° C., and of 8% steam or less, calculated upon the quantity of the benzol vapour. Said vapour mixture is condensed in a cooler 17 which, similarly to cooler 9, is connected with a water separator in such a manner that a crude benzol freed from water may be discharged at 18. A part of the crude benzol obtained in the cooler 17 may be suitably delivered as reflux at the top of the rectifier column 14.

Toluol vapours may be discharged at a lower point of the column 14 through the pipe line 19 leading to the cooler 20. Similarly the pipe line 21 and the cooler 22 serve for the recovery of the so-called solvent naphtha. Under certain conditions it may be advisable to connect in front of the coolers 20 and 22 a further auxiliary column in order to purify the vapours of toluol and solvent naphtha escaping from the column 14 before the vapours are condensed.

It is further possible to extract from the column 14 through the pipe line 23 a residual oil rich in naphthalene which, if the residual oil is cooled down to normal temperature (15° C.) within the pan 24, crystallizes out readily. The mother liquor from such naphthalene crystallization in the pan 24, which mainly consists of certain wash oil constituents, flows through the pipe line 25 into the collecting main 7 for regenerated (denuded) wash oil.

The residual oil, freed from the low boiling constituents in the column 14, flows into the collecting main 7 through the pipe line 26.

In the foregoing I have described my invention on the basis of wash oil treatment as used in the coal distillation industry, but I wish it clearly to be understood that the principle of my invention, i. e. the primary distillation of the enriched oil or solvent in the presence of steam at comparatively low temperatures, and the distillation of the condensate vapours from such primary distillates, after separating of the condensed water, by means of a pipe still, or another similar distilling apparatus, may be advantageously used for the treatment of other washing media or solvent, such as the washing oil used for absorbing light hydrocarbons from other gases or vapours, and therefore my invention is in no way limited to the mode of carrying out as described and explained hereinbefore.

I have now above described my present invention on the lines of a preferred embodiment thereof but my invention is not limited in all its aspects to the mode of carrying it out as described and shown, since the invention may be variously embodied within the scope of the following claim.

I claim:

A process for the continuous treatment of light-hydrocarbon enriched wash-oil of the character of benzol-absorbent wash-oil by distillation in the presence of steam with the recovery of the light-hydrocarbons from the absorbent wash-oil in several fractions of sharply defined boiling limits, comprising the steps: distilling the light-hydro-

carbon laden wash-oil in the presence of steam in such manner that the absorbed light-hydrocarbons and a part of the wash-oil are driven off as vapours; condensing the vapours produced; separating water from the condensate; heating the condensate very quickly to a temperature at which the absorbed light-hydrocarbons are vaporized, by indirect heating while the condensate flows through a coil in a pipe still; and then

fractionating the vapours from the pipe still in a rectifying apparatus, and in which the vapors from the pipe still are fractionated with a limited quantity of steam in the fractionation step, the quantity of steam being such that at the top of the rectifying column a mixture consisting of benzol and about 8% by weight of steam or less (based upon the benzol vapours) flow off.

ADOLF SCHMALENBACH.
